Philip S. Hopkins
ATTORNEY

UNITED STATES PATENT OFFICE.

LESLIE S. HALL, OF ERIE, PENNSYLVANIA, ASSIGNOR TO WILLIAMS TOOL CORPORATION, OF ERIE, PENNSYLVANIA.

DIE HEAD FOR THREADING MACHINES AND THE LIKE.

Application filed June 20, 1925. Serial No. 38,599.

My invention relates generally to a die head, particularly those which are adapted to cut thread on pipe, bolts or other materials.

The primary object of my invention is to provide a mechanism for opening and closing the die head and which has combined therewith a micrometer adjustment operable after the head has been closed to approximately the required point.

10 Another object is to provide indicating means by which the operator of the machine can tell when the proper length of thread has been cut without the necessity of guess work heretofore employed by watching the 15 actual threading operation, and also check the accuracy of the die setting.

A still further object is to provide means whereby the opening and closing mechanism may be adjusted on the cam plate controlling 20 the movement of the chaser or die holder.

Still another object is to provide such a mechanism as will be simple in operation, inexpensive to manufacture and yet positive and precise in its movement.

25 Other objects and advantages in details of construction and operation will be apparent as the description proceeds, reference being had to the accompanying drawing wherein like reference numerals indicate like parts.

30 In the drawing:-

Figure 1 is a front view of my improved die head showing the opening and closing mechanism thereon.

Figure 2 is a top plan view of the mechanism.

Figure 3 is a side view of the head showing in outline, the adjusting mechanism and the indicating means.

Figure 4 is a detail cross sectional view 40 illustrating the relation between the removable pin carried by the die holders and the closed openings in the cam plate.

It will be understood, of course, that while my invention has been illustrated and will be 45 described as applied to a die head for chasing or cutting thread on pipe or bolts, the same is capable with slight modifications of adaptation to many other machines, wherein the cutting dies are adapted for opening and closing.

50 My improved head includes the rigid head stock 1, provided at equally spaced intervals around its circumference with openings 2,

providing slideways extending from the periphery of the head stock through to the 55 opening 3, centrally thereof, into which the pipe, bolt or other material to be threaded is fed.

Slidably mounted within the openings 2 are chaser holders 4 carrying at their inner 60 ends the chaser bits or thread cutting dies 5. These chaser bits are secured in position in any suitable manner as by means of clamping plates 6.

A circular bushing or ring bearing 7 lines 65 the opening 3 and is secured in position to the head stock 1, as by bolts 8. Rotatably mounted upon this ring bearing and lying flush against the face of head stock 1, is a 70 cam plate 9 provided on its inner face with cam grooves or slots 10, as shown in dotted lines in Figure 1. Each of the chaser holders 4 is provided intermediate its end with a headed pin 11 seating in a smooth bored opening 10^a, the head of which engages within the slot or groove 10 in the cam plate. It 75 will be understood therefore that with the parts assembled in this relation, rotation of the cam plate will result in an even and uniform sliding movement of the chaser holders 80 within their slideways 2.

Openings are provided at equal distantly spaced points on the face of the cam plate, which openings are covered with the removable cap 12. The position of these openings 85 is such that when the chaser holders are moved outwardly by the cam plate to the limit of their movement, the headed pin 11 will be disposed directly beneath the opening. This enables the operator by removing 90 the cover cap 12 to withdraw the headed pins 11 from the openings 10^a whereupon the entire chaser holder may be removed from the head for cleaning or other purposes.

Rigidly secured to the top of the head 95 stock 1, as by screws 13, in an upstanding bracket 14. The upper end of this bracket 14 is provided with an opening through which passes a screw threaded shaft 15. The portion of the bracket through which the 100 screw 15 passes, is also recessed as at 16 to receive a nut or thumb piece 17, through which the screw 15 is threaded and by means of which said screw is adjusted within the bracket 14. A lock nut 18 is received upon 105 the outer projecting end of the screw 15

whereby said screw may be securely locked in its adjusted position.

The inner end of screw 15 carries an eye 19 through which passes the pivot 20 carrying at either end the bifurcated forks or fingers 21 and 22 of a link 23.

Secured to the opposite end of the link 23 as by means of bolts 24, is one end of a lever or operating handle 25, whereby said link 23 may be rocked on its pivot 20 as shown in dotted lines in Figure 1.

Pivoted adjacent the lower side of link 23 and between the ends thereof, as at 26, is one end of the link 27 carrying at its opposite end means for removably and adjustably engaging the edge of the cam plate 9. This means comprises a block or shoe 28 provided with a shoulder 29 for engaging the rear side of the cam plate 9, the edge of the head stock 1 being cut away at this point to receive said shoulder. A clamping plate 31 is provided with a projecting lip 32 for engaging the front surface of the cam plate 9, and may be loosely or tightened thereon by means of bolt 33 passing through the shoe 28 and clamping plate 31 and provided at its outer end with a tightening screw 34. The inner end of bolt 33 passes through link 27 and is secured thereto as by means of a nut 35.

A pointer or other indicating marks 36 is mounted upon the periphery of the cam plate 9 at one side thereof to register with a scale 37 upon the adjacent edge of the head stock 1.

The operation of my invention is as follows: Assuming the parts to be in the position shown in Figure 1, and it being desired to thread the section of pipe of a larger diameter than that for which the chasers are set, the operator first loosens the nut 34 on the clamping plate 31 and grasping the handle 38 mounted upon the edge of the cam plate 9, rotates said cam plate to open the die until the pointer or indicator 36 indicates on the scale 37 that the dies are in proper position to thread a pipe of the desired diameter. The screw 34 is then again tightened thus securing the cam ring to the link 27. The handle 25 is then raised to the position shown in dotted lines in Figure 1, which operation through the medium of link 27 acts to open the die for the reception of the pipe.

The end of pipe is then placed in position to be engaged by the chaser bit 5 and the handle 25 again lowered, thus bringing the chasers back to the point to which they were previously set as indicated by the scale 37. If, however, there should have been a slight error in the setting of the clamping plate 31 on the cam plate 9, or if the pipe should vary slightly in its supposed diameter, it is not necessary to again loosen the screw 34 and readjust the dies through the medium

of the handle 38 or the link 27. It is only necessary in such an instance to loosen the set screw 18 on the adjusting screw 15 and rotate the thumb piece 17 which moves the screw 15 outwardly or inwardly as may be desired, and at the same time imparting such movement to the link 23 and consequently to the link 27, which in turn moves the cam plate 9. This micrometer adjustment may be continued until the scale and pointer 36 and 37 indicate that the proper adjustment has been made whereupon the set screw 18 may be again tightened and the die is ready for operation.

Upon completion of the threading operation, the operator merely grasps the end of the handle 25, raising it upwardly which immediately opens the die and permits the threaded end of pipe to pass on to the opening 3 in the head where it may be chamfered or cut off as may be desired.

It will be understood too that should there be an automatic receiving attachment on the machine whereby the cam plate 9 is moved as the threading operation progresses whereby to cut a taper thread, the scale and pointer 36 and 37 will function to indicate the length of thread being cut. The operator watching this indicator may at the proper moment raise the handle 25 and open the die promptly at the proper time.

The simplicity and the many advantages of this device will be obvious to those skilled in the art. They will also understand that the construction as shown and described herein is susceptible to various changes in details of construction without departing from the spirit and scope of the invention.

I do not limit myself therefore to the exact structure shown other than by the appended claims.

I claim:

1. A die head comprising movable chaser holders, a cam plate for moving said holders, a bracket on said head, an adjusting screw threaded through said bracket, pivot means on one extreme end of said screw, a lever pivoted at one end to said means, a link pivoted to and intermediate the ends of said lever and within the vertical plane thereof, said link carrying clamping means engaging said cam plate and including a member frictionally engaging the edge of said plate and adjustably secured thereto.

2. A die head comprising movable chaser holders, a cam plate for moving said holders, means removably mounted in said holders connecting said cam plate and said holders, said cam plate being provided with means of access to said connecting means to permit the removal thereof through said plate.

3. A die head comprising movable chaser holders, a cam plate for moving said holders, headed studs removably mounted in said

holders connecting the same with said cam plate, said cam plate being provided with openings permitting access to said studs for the withdrawal thereof.

5 4. A die head comprising movable chaser holders, a cam plate for moving said holders, headed studs removably mounted in said

holders connecting the same with said cam plate, said cam plate being provided with openings permitting access to the said studs 10 for the withdrawal thereof, and closure caps for said openings on the outer face of said cam plate.

LESLIE S. HALL.
